ATTORNEYS.

UNITED STATES PATENT OFFICE

JOHN S. FORBES, OF PHILADELPHIA, PENNSYLVANIA, ASSIGNOR, BY MESNE ASSIGNMENTS, TO YATES & GRANT, INC., OF DETROIT, MICHIGAN, A CORPORATION OF MICHIGAN

MAGNETIC RAZOR-CONDITIONING DEVICE

Application filed March 17, 1927. Serial No. 176,195.

My invention relates to magnetic razor conditioning, my object being to provide a simple and effective means of producing or maintaining a good edge on a razor blade by magnetic influence. How this and other advantages may be realized through my invention will appear from my description hereinafter of certain devices conveniently embodying it.

In the drawings, Fig. I is a tilted view of a device suitable for the purposes of my invention, including a magnet in a case and a keeper for the magnet associated with a cover for the case,—the cover and case being oppositely tilted.

Fig. II shows a longitudinal vertical section through the device with the cover and keeper in place on the case and magnet.

Fig. III shows a longitudinal section of the magnet and case alone, with a safety 20 razor blade under treatment by the magnet in one manner.

Fig. IV is a similar view showing a different manner of treating a razor blade.

Fig. V is a view similar to Fig. III, showing a somewhat different construction.

Fig. VI shows a longitudinal section through a cover and keeper for the case and magnet shown in Fig. IV.

Fig. VII shows a transverse section of the 30 device with a razor therein under treatment.

As shown in Fig. I, the device comprises a magnet 10 of bar form in a case 11, and also a cover 12 for the case 11 associated or equipped with a keeper or armature 13 for 35 the magnet 10. In the present instance, the case 11 projects above the magnet 10, and the ends of the keeper 13 engage inside the up-standing case, in its corners, so as to maintain the cover 12 in proper position. The 40 ends of the keeper 13 are turned or bent downward at 14 and 15, so as to reach and engage the ends of the magnet 10. The magnet 10 may be a permanent magnet and the keeper 13 a strip of soft iron; while the case 45 and cover 12 may be of any suitable non-magnetic material, such as a moldable composition or compound like bakelite. As shown, the magnet 10 is secured to the bottom of the case 11 by rivets 16, and the keeper 13 50 is secured to the cover 12 by rivets 17. As

shown in Fig. II, there is slight clearance between the upper edge of the case 11 and the lid 12 when the keeper projections 14, 15 rest on the magnet 10.

As shown in Figs. I, II, III, and IV, the 55 ends of the magnet 10 are preferably provided with transverse engagement means for aligning and maintaining a safety razor blade in proper treating position with reference to the magnet, such means being shown in the form of saw-tooth grooves 18, 19, across the ends of the flat magnet bar. Also, one end of the magnet 10 is bevelled as at 20 to afford a more suitable treating face or surface. The keeper end 14 is squared off, and the end 15 bevelled in correspondence with the magnet bevel 20, so that both keeper ends shall make good contact with the magnet ends over ample areas. 60

Figs. III and IV illustrate the use of the 65 device, with the cover 12 and keeper 13 removed, to treat a safety razor of familiar type and form, comprising a blade 21, a guard 22, a clamp head 23, and a handle 24, with adjustable connection to the clamp head. 70

As shown in Fig. III, the ordinary shaving tension on the blade 21 has been relaxed, so as to allow it to resume its normal flat form. The razor has been laid on the device with the usual pronged edge of the guard 22 resting in the groove 18 and the handle 24 resting on the other end of the case 11. Accordingly, the blade 21 stands normal to the surface of the magnet end beyond the groove 18, with its cutting edge very close indeed to the magnet, yet out of contact therewith. After one edge of the blade 21 has been treated in this manner for a period of, say, half a minute or more, the razor may be reversed and the other edge similarly treated. While the blade 21 may be left under treatment much longer than the short period above mentioned, yet this short period will generally suffice to produce most, at any rate, of the possible beneficial effect on the blade. 80

Figs. V, VI and VII illustrate a device differing from that of Figs. I to IV in being longer and deeper, so as to contain a razor while under treatment. In the present instance, the cover 12^a extends some distance 85 90 95 100

down around the keeper or armature 13^a, instead of being a mere flat piece as in Figs. I and II. The downturned ends 14^a and 15^a of the keeper 13^a are correspondingly longer, 5 so as to afford depth for accommodating the whole razor therewithin when the cover 12^a is on the case 11^a. The case 11^a is also provided with supports for the razor, in the form of transverse blocks 26 with centrally 10 located curved notches 27 (Fig. VII) to accommodate the razor handle 24. The cover 12^a has similarly notched blocks 28 to fit over the handle 24 and hold the razor in definite position in the case 11^a,—i. e., the position 15 required for treatment of the edge of the razor blade 21 in substantially the same ways as illustrated in Figs. III and IV. The length or depth of the downturned armature ends 14^a, 15^a is preferably such that the upper 20 prongs of the guard 22 just about engage (or fail to engage) the keeper 13; and thus the upper edge of the blade 21 will lie very close to the keeper 13, so as to be affected by the induced magnetism therein. When 25 treated as in Fig. III, the blade 21 lies normal to both magnet 10^a and keeper 12^a; while when treated as in Fig. IV, the blade is approximately normal to the keeper, as well as truly normal to the bottom of the groove 19^a 30 (Fig. V).

Having thus described my invention I claim:

1. A device of the character described comprising a bar magnet with engagement means for coacting with a safety razor mounting extending alongside thereof to maintain the blade of said razor in magnetic treating position with respect to said magnet.
2. A device of the character described comprising a bar magnet and means for supporting a safety razor parallel therewith, and with the plane of its blade substantially normal to the adjacent magnet surface.
3. A device of the character described comprising a bar magnet for treating a safety razor blade and an armature for said magnet, said armature and magnet affording between them a housing space for a safety razor.
4. A device of the character described comprising a treating magnet and an armature therefor affording space between them for housing a safety razor with the plane of its blade substantially normal to both.
5. A device of the character described comprising a bar magnet and an armature therefor affording space between them for a safety razor extending substantially parallel with them, and cooperating means carried by 60 armature and magnet for supporting and holding the razor in that position.
6. A device of the character described comprising a bar magnet with engagement means for maintaining a mounted safety razor blade in magnetic treating position with re-

spect to said magnet, and a cover for said magnet embodying an armature therefor.

7. A device of the character described comprising a magnet with a transverse bevel affording a treating face normal to a mounted safety razor blade under treatment, and a cover for said magnet embodying a correspondingly bevelled armature.

8. A device of the character described comprising a treating magnet with a case projecting above it, and a cover for said case provided with an armature for the magnet adapted to engage inside the case and thereby maintain the cover in proper position thereon.

In testimony whereof, I have hereunto signed my name at Philadelphia, Pennsylvania, this 28th day of February, 1927.

JOHN S. FORBES.
